(57) **CLAIM**

The ornamental design for a candlestick, as shown and described.

DESCRIPTION

FIG. 1 is a front, right, and top perspective view of a candlestick, showing my new design;

FIG. 2 is a front, left, and bottom elevation view thereof;

FIG. 3 is another front, right, and top perspective view of the candlestick of FIG. 1 in a state of use;

FIG. 4 is a front elevation view thereof;

FIG. 5 is a left side elevation view thereof;

FIG. 6 is a top plan view thereof;

FIG. 7 is a bottom plan view thereof; and,

FIG. 8 is a cross-sectional view taken along line 8-8 of FIG. 4.

The broken lines shown in the drawings are included for the purpose of illustrating environmental structure and form no part of the claimed design.

1 Claim, 8 Drawing Sheets
